C. J. BEEMAN.

DOOR,

APPLICATION FILED MAY 12, 1917.

1,260,858.

Patented Mar. 26, 1918.

UNITED STATES PATENT OFFICE.

CORNELIUS J. BEEMAN, OF AKRON, OHIO.

DOOR.

1,260,858.

Specification of Letters Patent. Patented Mar. 26, 1918.

Application filed May 12, 1917. Serial No. 168,208.

To all whom it may concern:

Be it known that I, CORNELIUS J. BEEMAN, a citizen of the United States, residing at 617 Upson St., Akron, in the county of 5 Summit and State of Ohio, have invented new and useful Improvements in Doors, of which the following is a specification.

This invention relates to improvements in doors for closing large doorways in such 10 structures as barns, garages, etc. The object of the invention is to provide a door or closure member especially adapted for use in connection with a wide doorway such as are commonly employed for garages, etc., 15 where for various reasons, such as lack of space, the use of a swinging, lifting or folding door is not entirely feasible and where it is especially practicable to bodily move the entire door used for closing a wide doorway 20 into a position at an angle to the wall containing the doorway as for instance along an adjacent side wall to thereby economize space while at the same time leaving the doorway entirely free for use. Furthermore, 25 the invention contemplates the provision of means for accomplishing the foregoing result in such a manner that the shifting of the door may be done with a minimum amount of labor and when the door is in its 30 open or inoperative position the door does not interfere with the free and unhampered use of the doorway, and yet said door is entirely capable of being moved into proper position for effectually closing the doorway 35 when moved to its operative position.

With the foregoing and other objects in view, the invention consists in the novel construction, combination and arrangement of parts constituting the invention to be hereinafter specifically described and illustrated 40 in the accompanying drawings which form a part hereof wherein is shown the preferred embodiment of the invention, but it is to be understood that changes, variations 45 and modifications can be resorted to which come within the scope of the matter herein-after claimed.

In the drawings in which similar reference numerals indicate like parts in the different figures,

Figure 1 is a horizontal sectional view taken approximately on line 1—1 of Fig. 2.

Fig. 2 is a view looking from the interior of a structure provided with an opening 55 with a wide doorway and showing my improved door in its operative position with re-

spect to said doorway, said view being taken approximately on line 2—2 of Fig. 1, and Fig. 3 is a sectional view taken approximately on line 3—3 of Fig. 2.

Referring to the drawings in detail it will be assumed for the purpose of illustrating the present invention that it relates to a closure door for an ordinary garage having a ceiling 1, a front wall 2 and one or more 60 side walls 3. The front wall is provided with a wide doorway 4. Extending along the side wall 3 and preferably secured to the ceiling 1 is an overhead straight track 5, and extending along the front wall 2 and 65 extending across the opening 4 is an overhead track 6. Parallel with the track 5 is a similar track 7, and the tracks 6 and 7 are connected by an arcuately formed integral track 8. These tracks 5 to 8 inclusive are 70 all similar and are preferably supported from the ceiling or roof 1 and as the supporting means and tracks are of uniform construction a description of one is believed to be sufficient for the understanding of 75 them all. Each track consists of an inverted trough-shaped member 9 the upper portion 10 of which is arcuately-formed and with the side walls 11 in approximate parallelism and with the lower edges of the walls 11 upwardly and inwardly turned toward each other to provide a pair of parallel tracks or bearing surfaces 12. These tracks 12 are in 80 parallelism longitudinally of the entire device and are separated a desired distance 85 for the purpose for which they are to be utilized and constitute rails for the reception of supporting wheels to be later described. The various tracks are supported by brackets, all of uniform construction and 90 hence a description of one is believed to be sufficient for the understanding of all. Each bracket consists of a head 13 which is preferably secured by any suitable holding means to the under face of the ceiling 1 of 95 the building and from the head 13 depends an integral stem 14 the lower portion of which is provided with divergent furcations 100 15 the lower portions or edges of which are inwardly bent at 16 and are clenched over 105 the lower portions of the walls 11, for sustaining the track in position. In practice the arcuate portion 8 connecting the portions 6 and 7 of the track is formed upon the arc of a perfect circle preferably having a relatively long radius.

The door employed may be of any con-

struction and consists of two or more members hinged together, the number of members of each door depending upon the width of the doorway, weight, convenience and other factors not necessary to here describe. In the drawings the door shown comprises three members, 17, 18 and 19 pivotally united together by means of ordinary hinges 20. The three members are of sufficient width to overlap and entirely close the opening 4 in the wall 2 when the door is moved to its operative or closed position. In practice it is preferable to provide the door 19 which is adjacent to the straight track 5 with an extending arm 21. The entire door made up of the members 17, 18 and 19 is arranged to be suspended from the tracks 5, 6, 7 and 8 the preferable means for suspending the door is a plurality of trolleys all of which are similar and consequently a description of one is believed to be sufficient for the understanding of them all. In practice where a three membered door is employed the door 17 will be provided with two trolleys 22 and 23 positioned at the opposite upper corners of the door and the door 18 with a trolley at its upper right hand corner and the extension or arm 21 on the door 19 will be provided with a trolley 25. The means of attaching the various trolleys to the door consist in forming recesses in the upper edge of the door in which are socket forming members 26 provided with upper walls 27 separated from the lower faces of the recesses where the sockets occur by spaces 28 and in the upper walls 27 are vertical apertures 29. Each trolley consists of an upright stem 30 having the lower end 31 thereof threaded and arranged to extend through an aperture 29, and each provided within a recess 28 with nuts 32. The upper end of each stem is provided with a head 33 through which extends a shaft 34 on each end of which is mounted a grooved wheel 35 so positioned as to run on one of the rails of the track 12. The trolley 25 will be positioned so as to run on the overhead track 5 and the remaining trolleys 22, 23 and 24 are arranged to run on the combined tracks 6, 7 and 8. When the door is in its closed or

operative position it will be disposed as shown in solid lines in Figs. 1 and 2. When it is desired to move the door to its open or inoperative position the operator draws the door 19 to the right in Fig. 1 causing the trolley 25 to run along the track 5 away from the wall 2 and as the arm 21 of the door 19 moves to the right in Fig. 1 the trolleys 22, 23 and 24 of the other members 17 and 18 of the door are drawn along the track 6 and follow over the curvilinear or arcuate portion 8 onto the track 7 which is parallel with the track 5 and when in its completely inoperative position it will assume the position shown in dotted lines in Fig. 1, with the trolley 25 of the member 19 on the track 5 and the trolleys 22, 23 and 24 of the other members of the door on the straight portion 7 of the other track. In closing the door the operation is reversed. In practice a stop or lug 36 may be provided near the floor of the building for holding the loose lower end of the member 17 of the door and the remaining members 18 and 19 are provided with ordinary locking bolts 37 for holding them in their closed or operative position.

I claim,

The combination with a structure having two walls arranged in angular relation with respect to each other one of which is provided with a doorway, of a plurality of overhead tracks, two of which are parallel and arranged along the unopened wall and another track along the wall provided with an opening, said last named track connected with the inner one of the first pair of tracks by an arcuately curved portion, a door comprising a plurality of units hinged together, a trolley secured to the upper portion of each unit, one trolley on one end of said door arranged to run on the outer one of said first pair of tracks along said unopened wall and the trolleys on the other units arranged to run on the inner parallel track, the arcuate track and the track along the wall having the opening.

In testimony whereof I have hereunto set my hand.

CORNELIUS J. BEEMAN.
